UNITED STATES PATENT OFFICE.

HENRY L. C. WENK, JR., OF NEW YORK, N. Y.

NAIL.

1,206,068.

Specification of Letters Patent. Patented Nov. 28, 1916.

Application filed December 4, 1915. Serial No. 64,974.

To all whom it may concern:

Be it known that I, HENRY L. C. WENK, Jr., a citizen of the United States, residing at Brooklyn, in the county of Kings, city 5 and State of New York, have invented certain new and useful Improvements in Nails, of which the following is a specification, reference being had therein to the accompanying drawing.

- 10 My invention relates to certain new and useful improvements in nails or fastening devices, having for their chief object the effective use in securing corrugated iron roofing and walling, sheet metal cornice 15 work and flashing in position, the value of the same being the fastening of solidly corrugated or plain sheets to buildings, and at the same time the prevention of a leak where the nail is driven through the iron.
- 20 The invention consists essentially in a nail having a head of relatively soft non-corrosive metal, said head being provided with one or more thin flaring flanges projecting below the base thereof and slanting outwardly 25 from the center so as to make a snug watertight joint when the nail is driven tightly in position. The nature of the head of the nail keeps the moisture from corroding the iron wherever the galvanizing is broken 30 through at the point where the nail is driven in. The head of the nail being of lead or other soft metal is not liable to rust or to be otherwise destroyed, and, thence, is protected 35 from corrosion, the same being an important point since with the ordinary nail, even though it is galvanized before driving, the same often destroys or breaks off most of the galvanizing from the head and thereby exposes the head to corrosion.
- 40 The invention, therefore, consists essentially in the construction, arrangement and combination of the various parts, substantially as will be hereinafter described and then more fully pointed out in the claims.
- 45 In the accompanying drawing illustrating my invention: Figure 1 is a perspective view of a nail embodying my present improvements; Fig. 2 is a side elevation of the shank and shows the head in section; Fig. 50 3 is a sectional view of a modified form of the head.

Similar characters of reference designate corresponding parts throughout the different figures of the drawing.

55 A nail obviously consists of two principal parts the shank and the head.

1 designates the shank, which may be in the form of an ordinary wire nail with the pointed end 2 and the opposite flat driving end 3, which with a nail as ordinarily 60 formed, constitutes the common head. Although I have shown this wire nail with a round form and of the style illustrated, I do not wish to be restricted thereto, but 65 reserve the liberty of practising the invention with other forms and shapes of nail shanks, either round or square, or of wire or other material, within very wide limits inasmuch as the invention is broadly applicable for use with any kind of a shank.

70 4 denotes the head of my improved nail. It is usually of lead, though it may be of any other relatively soft metal which is not liable to corrode. The head 3 and contiguous end of the shank 1 are embedded within 75 the head 4, as indicated in Figs. 2, 3 and 4 of the drawing, said soft metal head being cast upon the end of the shank. The upper part of the head 4 which constitutes the driving surface is preferably of convex or 80 semi-circular form and is flat on its underside at 5.

85 The flat underside 5 of the head 4 is provided with an integral flaring and comparatively thin flange 6. This flange springs from the lower face 5 of the head 4 at a point part way between the peripheral edge of said face 5 and the shank 1 so that a portion of the face 5 lies outside of the flange 6. Flange 6, therefore, has an inner substantially concave or conical recess around 90 and adjacent to the shank 1 which occupies the center of the flange 6, the latter being concentric therewith and removed a proper distance therefrom so that the circular periphery of the flange 6 is substantially below the peripheral edge of the face 5.

95 The head 4 with its outwardly flaring flange 6 is cast around the head 3 and the upper portion of the shank 1 of the nail so that the parts are firmly united together. When the nail is driven through the iron of the corrugated or plain roofing or other part, which it is desired to secure in place, it is obvious that an opening is made in the corrugated roofing which unless thoroughly 100 protected would admit moisture by affording a space around the nail through which water, rain or dew might come into contact with the unprotected inner side of the work and damage the same. With my improved head however, carrying the flange 6, it will 105 110

be observed that when the nail is driven home, the flange 6 will flatten between the iron surface and the head face 5 and thus conform to the surface of the iron against 5 which the head is being driven and make a snug and water-tight joint which will become tighter the more securely the nail is driven, and in this way the shank of the nail will be protected against moisture, and also 10 the opening through which the nail is being driven will be so completely closed and covered that no moisture can possibly find its way through the same.

Sometimes I find it convenient to employ 15 the form of the invention illustrated in Fig. 3 which shows not only the flaring flange 6, but a concentric inner similar flange 7 similarly integral with the head 4 and springing from the base 5 at a point between the 20 flange 6 and the shank 1, though not touching the shank, being removed a short distance therefrom. This extra auxiliary or supplementary flaring or similar flange 7 insures a more effective water-tight joint 25 around the shank 1 and gives therefore a double protection. While I have thus shown one extra flange, it may be possible in other cases to further multiply the number of flanges.

30 Many other changes in the details of construction of the various parts may be made without exceeding the scope of the invention, and I, therefore, reserve the liberty of making such changes in the details consist- 35 ent with the scope of the appended claims as may be found necessary from time to time in order to achieve the best results.

With a nail of this kind there will be a very firm connection of the parts with which it is used, and a very effective prevention of 40 rust and corrosion; also a construction like this is lighter and has an advantage in saving over other similar nails in the way of the material used.

Having thus described my invention, 45 what I claim as new and desire to secure by Letters Patent, is:

1. In a nail, the combination of a shank, and a head of softer metal, from the lower face of which head at a point between the 50 peripheral edge of said face and the shank projects a comparatively thin outwardly flaring flange, there being a concave recess within the flange and immediately around the shank, and there being also a recess between the outer periphery of the flange and the adjacent peripheral edge of the lower face of the head.

2. In a nail, the combination of a shank, and a head of relatively soft metal, said 60 head being formed on its underside with a flat face provided with a dependent flaring flange concentric with the shank, and there being a concave recess within the flange immediately around the shank, and there being also an angular recess between the lower face of the head and the adjacent outer surface of said flange, the outer peripheral edge of the flange being directly below the outer peripheral edge of the lower face of 70 the head.

In testimony whereof I affix my signature.

HENRY L. C. WENK, Jr.
